UNITED STATES PATENT OFFICE.

TILGHMAN D. TERRY, ALONZO CASE, AND CHARLES LARKIN, OF KNOB-NOSTER, MISSOURI.

IMPROVEMENT IN WHEEL-PLOWS.

Specification forming part of Letters Patent No. 142,964, dated September 16, 1873; application filed April 5, 1873.

To all whom it may concern:

Be it known that we, TILGHMAN DABNEY TERRY, ALONZO CASE, and CHARLES LARKIN, of Knobnoster, in the county of Johnson and State of Missouri, have invented certain new and useful Improvements in Sulky Cultivators and Plows; and do hereby declare that the following is a full, clear, and exact description thereof, reference being had to the accompanying drawings and to the letters of reference marked thereon, which form a part of this specification.

The nature of our invention consists in the construction and arrangement of a sulky cultivator and plow, as will be hereinafter more fully set forth.

In order to enable others skilled in the art to which our invention appertains to make and use the same, we will now proceed to describe its construction and operation, referring to the annexed drawing, in which—

Figure 1 is a plan view, and Fig. 2 a side elevation, of our machine. Fig. 3 is a section of a wheel used for cutting stalks and weeds.

A represents the tongue, which extends back and has the axle B passing through it a suitable distance from its rear end. One end of the axle B is bent, forming a crank, a, and on the end of the same, as well as on the other end of the axle, is placed a driving-wheel, C. The wheel on the crank a is intended to run in the furrow, and can be raised or lowered at will by means of a lever, b, attached to the axle B, and engaging in a segment rack-bar, d', attached to the tongue A, and holding the axle with the crank in any position desired. D represents a wheel to be attached, when desired, on either end of the axle for cutting stalks and weeds. This wheel has two rims, d and e, the spokes being attached to the outer rim d, and this rim forming a cutter on its outer edge, while the inner rim e is simply attached to the side of the outer rim and spokes, and has the cutter formed along its inner edge, as fully shown in Fig. 3. In a staple, f, attached to the tongue A, a suitable distance in front of the axle, is pivoted a beam, G, which rests upon the rear end of the tongue, and has the seat E supported thereon. At the outer end of the beam G, on

the side thereof, is pivoted another beam, G', to which the plow H and revolving colter J are attached, the front end of said beam G' resting upon a support, k, attached to the tongue. On the side of the beam G, between it and the beam G', is pivoted a lever, J', having a stud, i, on its lower end, projecting inward under the beam G. From the lever J', at or near the pivot-point, projects an arm, h, forward at right angles, said arm being, at its outer end, provided with an outward-projecting stud, i'. The studs i and i' may be provided with friction rollers, if so desired.

By means of the lever J' and its arm h, the plow is raised out of the ground, when so desired, in the following manner: The stud i, the lever being pulled backward, first strikes the under side of the beam G', raising its front end so as to lift the point of the plow first. Then the stud i' runs up the inclined rear end of the tongue A, raising the rear ends of both beams G and G', and thereby lifting the heel of the plow also. The upward movement of the beam G is limited by a band or staple, f', surrounding the same and attached to the tongue. Three horses are intended to be used with this plow, two on the right and one on the left side of the tongue A, thus bringing the greatest amount of force on the same side of the machine as the plow. On the tongue A is secured a box, m, through the front end of which passes the double-tree K, the same being pivoted by a bolt, n, passing through an oblong slot in the box m, allowing the double-tree to move backward and forward to the extent of said slot. The bolt n also passes through and pivots one end of an equalizing-bar, L, which is placed on top of the double-tree and extends to the right side. M M M are three single-trees, attached one to each end of the double-tree and one to the outer end of the equalizing-bar L. In the center of the double-tree is attached a frame or box, s, having a roller, y, and in the rear end of the box m is another roller, z. A chain, x, is attached to the box m, passes around the rollers y and z, as shown in Fig. 1, and then attached to the outer end of the equalizing-bar L. By this means the draft of the three horses is perfectly equal-

ized, and the plow moved steadily without jerking to either side, and therefore making a straight and even furrow.

Having thus fully described our invention, what we claim as new, and desire to secure by Letters Patent, is—

1. The combination, with the tongue A, axle B, and wheels C C, of the bar G, hinged at its front end to the tongue and supporting the seat E, and the bar G' pivoted to the rear end of the bar G, and having the plow H and colter J attached to it, all substantially as herein set forth.

2. The lever J', with arm h and studs i i', and bars G, G', staple f', and support k, the several parts being constructed and arranged as and for the purpose specified.

3. The wheel D, constructed as described, with the outer and inner cutting-rims d e, substantially as and for the purposes herein set forth.

4. In combination with a plow arranged on one side of the center, as shown, the double-tree K, equalizing-bar L, single-trees M, rollers y z, and chain x, all arranged and operating substantially as and for the purposes herein set forth.

TILGHMAN D. TERRY.
ALONZO CASE.
CHARLES LARKIN.
